INSECTICIDES

Roy Cross, Kansas City, Mo.; Mary Forbes Cross
and First National Bank of Kansas City, execu-
tors of said Roy Cross, deceased

No Drawing. Application April 13, 1945,
Serial No. 588,247

4 Claims. (Cl. 167—30)

1

This invention relates primarily to certain types of insecticides which have proved to be unusually effective and at the same time have low toxicity to warm blooded animals. The active property of these insecticides is found in a benzene ring to which is attached one or more fluorine atoms. Illustrative of these substances are difluorobenzenes ($C_6H_4F_2$); fluorobenzene (C_6H_5F); difluoro diphenyl trichlorethane—1,1 bis(p-fluorophenyl) 2,2,2 trichlorethane—, for convenience called DFDT; difluor diphenyl dichlorethylene—1,1 bis(p-fluorophenyl) 2,2 dichlorethylene—; and fluorobenzoic acid

(C_6H_4FCOOH)

These are merely representative, DFDT and difluor diphenyl dichlorethylene being particularly effective.

While the methods of manufacture of many of these fluoro-phenyl products are subject matter of separate inventions, the following is illustrative of typical reactions:

As an example, difluorobenzenes may be produced by the reaction of dichlorbenzenes with mercury fluoride or with antimony fluoride, for example:

As an illustration of the yields in these and similar reactions in the manufacture of DFDT, 83% of a theoretical yield has been obtained. In the case of DFDT, a solution of 1/2% to 2% is ordinarily used. This solution may be made up in petroleum naphtha or kerosene and then sprayed for insects. In the case of flies, the number of flies killed is much greater than in the former insecticides of the type of pyrethrum solutions. In each type of insecticide there is an optimum concentration and an optimum condition for use. This is apparent to one skilled in handling insecticides.

I claim:

1. An insecticidal composition of matter comprising the combination of the active ingredient

1,1 bis (p-fluorophenyl) 2,2,2 trichlorethane, and a carrier of a petroleum hydrocarbon solvent.

2. An insecticidal composition of matter containing 1,1 bis (p-fluorophenyl) 2,2,2 trichlorethane as an active ingredient.

3. An insecticidal spray having 1,1 bis (p-fluorophenyl) 2,2,2 trichlorethane therein as an active toxicant.

4. An insecticidal composition comprising the combination of 1,1 bis (p-fluorophenyl) 2,2,2 trichlorethane as the active ingredient and a carrier miscible therewith.

2

ROY CROSS.
